UNITED STATES PATENT OFFICE.

MURRIT M. JEWETT, OF CORNING, NEW YORK.

COATING-MACHINE.

1,239,399.

Specification of Letters Patent. Patented Sept. 4, 1917.

Application filed November 2, 1916. Serial No. 129,207.

To all whom it may concern:

Be it known that I, MURRIT M. JEWETT, a citizen of the United States, residing at Corning, in the county of Steuben and State 5 of New York, have invented certain new and useful Improvements in Coating-Machines, of which the following is a specification.

This invention relates generally to coating 10 machines, and particularly to mechanism for coating candies and the like.

The primary object of the invention is to provide a machine by the use of which the 15 moistening and coating of candies or marshmallows is wholly automatic, and wherein the articles to be treated are evenly coated upon all of their surfaces. A further object of the invention is to provide a mechanism of this character wherein the coating 20 material is economized, and wherein such material is prevented from becoming lumpy during the operation. A still further object resides in the provision of a mechanism of this character by means of which the coating 25 operation is carried on in a sanitary manner.

Still further objects reside in constructing a mechanism of this character and for the purposes set forth which is featured by 30 the lack of complicated or intricate parts; which may be quickly and easily cleaned or repaired when required; which requires but a small amount of power for its operation; which requires no attention during the operation; and which combines efficiency with 35 simplicity of construction.

With these objects in view, together with others which will appear as the description proceeds, the invention resides in the novel 40 formation, combination, and arrangement of parts, all as will be described more fully hereinafter, described in the drawings, and particularly pointed out in the claims.

In the drawings:-

Figure 1 is a side elevation of a coating 45 machine constructed in accordance with the invention;

Fig. 2 is an enlarged longitudinal sectional view taken through the coating machine; and

Fig. 3 is an end view partly in section, of the coating machine.

The invention consists generally in the arrangement of a conveyer within a drum or container, the conveyer being adapted to 55 carry the articles to be coated through the drum, while the drum is equipped with mechanism for directing coating material upon the articles during their passage through the same. The conveyer is equipped 60 with means for turning or tumbling the articles while traveling, so as to expose all sides to the coating material.

In carrying out the invention, a suitable 65 frame or support 10 is provided, and upon which the mechanism for coating the articles is positioned. Rotatably mounted upon the frame 10 and in spaced parallel relation are shafts 11 and 12, to which are affixed supporting wheels 13. One of the shafts is provided 70 with a pulley 14, over which a belt 15 passes for transmitting rotary movement to the shaft. The belt may be passed over a pulley upon a suitable power shaft, not shown. Secured upon the shaft 12 preferably an 75 even distance between the supporting wheels 13 is a gear 16.

The drum used in carrying out the invention is indicated at 17, and has trackways 18 passing around the same adjacent the ends 80 thereof, and in which the supporting rollers or wheels 13 are adapted to engage to bear the weight of the drum and to permit of the latter rotating. It will be observed that the flanges on the trackways are so arranged as to prevent sliding movement of the drum upon the supporting wheels. The drum is also equipped with an annular rack 19, which is enmeshed with the teeth of the gear 16. As the shaft 12 is driven by the 85 belt 15, it is apparent that the drum 17 will, by reason of the gear and rack 16-19, rotate upon the support or frame, and by reason of the fact that the drum is supported by the supporting wheels 13, the said drum 90 may be rotated with the expenditure of but a relatively small amount of power.

The ends of the drum are provided with relatively large openings, which are closed 95 by heads 20. These heads are formed of 100

sectional plates as shown, the edges of which are provided with flanges 22 to engage behind the edges of their respective openings upon the interior of the drum. The heads 5 do not rotate with the drum, but are held stationary by means of brackets 23 upon the frame or support 10. The flanged construction of the head permits of the drum rotating relative to the heads without a great 10 amount of friction, and yet the said drum is rendered practically air tight. The head at the forward end of the drum as well as at the rear is provided with guides 24, within which a slidable gate 25 is arranged, the 15 said gates being adapted to close feed openings in the head. Through these openings, sugar, cocoanut, or other coating material may be introduced to the interior of the drum.

20 The conveyer for carrying the articles to be coated to the drum is shown more clearly in Figs. 2 and 3 of the drawings, and comprises an elongated cylinder or drum. This cylinder has its ends formed 25 of sheet metal, while the intermediate portion is of mesh indicated at 26. The open work or mesh portion of the cylinder is of substantially the same length as the drum, and the cylinder is disposed within the 30 drum at an angle to the axis of the latter. The metallic ends of the cylinder protrude beyond the extremities of the drum, and project through suitable openings formed in the heads 20 of the drum. Posts 27 are 35 secured upon the frame 10 and project upwardly therefrom beyond the ends of the drum, and these posts carry supporting rings 28 at their upper ends. These supporting rings are equipped with anti-friction 40 rollers 29, arranged in spaced relation around the rings and which support the extremities of the cylinder. An annular member 30 constituting a belt path is secured to the rear end of the cylinder, and over which 45 a belt 31 passes, the said belt being passed around the pulley 32 on the shaft 12. The pulley and belt arrangement is such that the cylinder will rotate in a direction opposite to that of the drum 17.

50 Arranged within the cylinder and extending substantially throughout the length of the same, is a spiral member or worm 33. This worm is fixed to the cylinder so as to travel therewith, and prevents the articles 55 conveyed by the cylinder from passing too rapidly through the same, and also assists in tumbling or turning the articles during rotation of the cylinder. A spout 34 may be provided at the lower or forward open end 60 of the cylinder, to guide the articles delivered from the said cylinder to direct them into a pan or receptacle placed beneath the spout for catching the finished or coated candies.

As a means for keeping the coating material thoroughly agitated during the operation of the machine, to prevent the material from becoming lumpy, and for conveying this pulverized material into the conveyer or cylinder, the inner annular wall of 70 the drum 17 is provided with a plurality of spaced pockets, indicated at 35 in Fig. 3 of the drawings. These pockets may be provided by securing a number of plates 36 to the annular wall of the drum in spaced 75 relation and around the periphery of the same. The plates are inclined slightly in the direction of rotation of the drum, and are secured to the wall of the drum at a slight angle to the axis of the latter. These 80 plates are disposed downwardly toward the rear end of the drum, so that as the said plates move upwardly as the drum rotates, fluent coating material such as sugar, cocoanut, or the like, will gravitate toward the 85 rear end of the drum. As the plates reach the upper limit of their travel, the matter held thereby will gravitate upon the conveyer or cylinder passing substantially centrally through the drum. To insure the 90 coating material being directed into the foraminous portion 26 of the cylinder, guide plates 37 are disposed longitudinally within the drum and upon opposite sides of the cylinder. These plates are secured at 95 their extremities to the heads 20, and form divergent side walls of hopper-like formation.

In operation, the coating material is introduced to the interior of the drum through the doors or openings 25. The candies or articles to be coated are, after the machinery for operating the drum and cylinder has been started, introduced to the interior of the conveyer or cylinder at the upper rearward end of the latter. The articles if not 100 of an inherent sticky nature, must be dipped or moistened prior to being deposited in the cylinder, so that the coating material will readily adhere thereto. As the cylinder rotates, the articles are tumbled, and gradually work downwardly toward the forward 105 open end of the cylinder. By reason of the worm or spiral 33, the articles are held against too rapid movement during the 110 operation. The spiral also assists in tumbling the articles, so as to present all sides or surfaces of the articles to the coating material directly through the foraminous wall. The drum rotates in the direction indicated by the arrow in Fig. 3, and the coating material will be carried in the pockets upwardly until the pockets are inverted, whereupon the material will be deposited in the 115 hopper formed by the plates 37 arranged in divergent relation within the drum. The material sifts through the foraminous wall of the conveyer and strikes the articles within the same. The articles are thus inti-

mately associated with the coating material. By reason of the fact that the rotating cylinder or conveyer inclines downwardly toward the forward end of the drum, the coating material will be carried by the said cylinder toward the forward end of the drum, and to return the material to the rear end of the drum the plates or blades 36 forming the pockets upon the inner periphery of the drum are disposed downwardly in their upward travel toward the rear end of the drum. By thus arranging the pockets, the bulk of the material conveyed thereby is directed into the hopper adjacent the rear end of the drum.

The coated articles are discharged from the cylinder at the lowermost or forward end of the latter, and may be collected in suitable receptacles.

20 I have described the drum and conveyer in the present disclosure as being of cylindrical formation, however, it will be understood that the invention need not be limited to these details. It is also obvious that the cylinder may be of a continuous length of sheet metal, provided with openings to permit of the introduction of the coating material. Other means also may be provided for supporting the drum and the conveyer.

25 30 While the present disclosure is that of what I believe to be the preferred embodiment of the invention, it is to be understood that the invention is not limited thereto, but that various changes may be made in the 35 construction, arrangement and proportion of parts, without departing from the scope of the invention, as defined in the appended claims.

What is claimed is:—

40 1. In a coating machine, a drum adapted to contain a coating material, means for conveying the articles to be coated through said drum, and means on said drum for conveying the coating material from the bottom to the top and to one end thereof and directing the same into the path traversed by said articles.

45 2. In a coating machine, a drum adapted to contain a coating material, a hopper in said drum, means for conveying the articles to be coated beneath the open end of said hopper, and means for conveying the coating material from the bottom of said drum to the top and to one end thereof depositing the same in said hopper.

50 3. In a coating machine, a drum adapted to contain a coating material, a conveyer comprising a foraminous rotatable shell arranged within said drum, and means for conveying the coating material from the bottom of said drum to the top and depositing it upon said shell.

55 4. In a coating machine, a drum adapted to contain a coating material, a cylindrical

foraminous shell rotatably arranged within 65 said drum, means for directing the coating material upon the top of said shell, and a worm in said shell.

5. In a coating machine, a drum adapted to contain a coating material, a foraminous 70 shell rotatably arranged within said drum with its axis disposed at an angle to that of said drum, and means within said drum for conveying the coating material from the bottom of said drum to the top thereof and 75 depositing it upon said shell.

6. In a coating machine, a rotatable drum adapted to contain a coating material, a foraminous shell rotatably arranged and angularly disposed within said drum, a hopper 85 in said drum above said shell, and means on said drum for conveying the coating material from the bottom to the top and to one end thereof and depositing it in said hopper.

7. In a coating machine, a rotatable drum adapted to contain a coating material, means within said drum for supporting the articles to be coated, and the inner surface of said drum being provided with pockets 90 disposed at an angle to the axis of said drum to carry the coating material upwardly and depositing the material onto said means.

8. In a candy coating machine, a rotatable 95 drum adapted to contain a coating material, plates secured to the inner periphery of said drum and being disposed at an angle to the axis thereof, and a conveyer passing through said drum and adapted to carry the articles 100 to be coated.

9. In a coating machine, a rotatable drum adapted to contain a coating material, plates projecting inwardly from the inner periphery of said drum and being disposed at an 105 angle to the axis thereof, and a conveyer passing through said drum and inclined downwardly.

10. In a coating machine, a rotatable 110 drum adapted to contain a coating material, plates secured to the inner periphery of said drum and projecting inwardly therefrom, the said plates being inclined from the front toward the rear end of said drum, and a conveyer passing centrally through said drum and inclining downwardly from the rear to the front end thereof.

11. In a coating machine, a rotatable 115 drum adapted to contain a coating material, stationary heads for said drum, a cylindrical foraminous shell rotatably mounted in said heads, and means for carrying the coating material from the bottom to the top of said drum and depositing it upon said shell.

12. In a coating machine, a drum adapt- 120 ed to contain a coating material, a forami- nous cylindrical shell rotatably mounted in said drum, a worm in said shell, and means

for carrying the coating material from the bottom, to the top and to one end of said drum and depositing it upon said shell.

13. In a coating machine, a drum, a rotary conveyer in said drum, the said drum and conveyer being adapted to rotate in opposite directions, means for directing coating material on said conveyer at one end thereof,

and means for feeding articles to said conveyer.

In testimony whereof I affix my signature in presence of two witnesses.

MURRIT M. JEWETT.
